W. S. TOWER

MACHINIST'S CLAMP

Filed April 10, 1923

INVENTOR
W. S. Tower.
BY
Albert E. Dietrich
ATTORNEY

UNITED STATES PATENT OFFICE.

WALTER S. TOWER, OF RACINE, WISCONSIN.

MACHINIST'S CLAMP.

Application filed April 10, 1923. Serial No. 631,208.

To all whom it may concern:

Be it known that I, WALTER S. TOWER, a citizen of the United States, residing at Racine, in the county of Racine and State of Wisconsin, have invented a new and Improved Machinist's Clamp, of which the following is a specification.

The invention resides in the provision of certain new and useful improvements in that class of machinists' clamps in which is embodied means whereby varied clamping surfaces may be presented to the work and in which means is included for adjusting the fulcrum of the working parts whereby the range of operation thereof may be varied.

The invention has for its object to provide a simple and compact construction of machinist's clamp, inexpensive to manufacture and easy to operate and which is capable of clamping parallel surfaces, tapered surfaces, or round surfaces and wherein is embodied means whereby the fulcrum of the working parts may be quickly and effectively changed in position for varying the range of clamping action of the same and wherein a more powerful action of the clamping parts is present than is had in the ordinary type of parallel clamp or C clamp.

With the above and other objects in view, the invention resides in those novel details of construction, combination of and arrangement of parts, all of which will be first fully described, then be specifically pointed out in the appended claims, reference being had to the accompanying drawing, in which:

Figure 1 is a side elevation of the invention in clamped condition.

Figure 2 is a rear end elevation of the clamp.

Figure 3 is a front end elevation of the clamp.

Figure 4 is a horizontal section taken substantially on the line 4-4 on Figure 1.

Figure 5 is an enlarged detail longitudinal section illustrating the yieldable fulcrum retaining means.

Figure 6 is a side elevation of the invention and illustrates a modified form of fulcrum retaining means.

In the drawing, in which like numerals of reference indicate like parts in all of the figures, I have illustrated the elements of my invention as practically embodied in

two main bodies, a movable jaw carrying member, and a base member providing a relatively fixed clamping jaw, the said bodies being separable from each other by snap action, as hereinafter described in detail.

The base member 1, of substantial T shape in cross section, includes a downwardly projecting reduced web 2 and, approximately centrally thereof, with an upward projection 3 of reduced thickness and which is provided with a plurality (two being shown) of fulcrum receiving cut out portions 4 which are cut on approximately 45° angles downward toward the point of clamping action and which are adapted to receive and provide fulcruming bearing portions for the fulcrum pin 5.

The fulcrum pin 5, above referred to is carried by the movable jaw carrying member and is the sole means of actual connection between the two main bodies hereinbefore referred to, and, from the following detailed description, it will be readily apparent that this sole connection may be quickly and effectively broken and rearranged, by snap action, for the purpose of changing the range of clamping action of my improved clamp.

The movable jaw carrying member consists of a pair of parallelly arranged side plates 6, of the contour clearly illustrated, the said plates being joined at their rear ends by the upset trunnions 7 of the pivot head 8 which is provided with a threaded bore 9 for receiving the clamping screw 10 having the turning head 11 and a base engaging end 12 adapted to seat in and coact with the bearing socket 13 formed in the rear top face of the base member 1. The fore ends of the plates are joined by the shouldered and upset cross pin 14 upon which the clamping jaw 15, provided with a flat clamping face 16 and a grooved clamping face 17 is pivotally mounted so that the said clamping faces may be reversed at will or permitted to conform to a tapered face-to-be-clamped, as may be desired.

Other shouldered and upset spacer pins 18 may be utilized to properly hold the side plates 6 in their desired spaced and parallel relation.

From Figure 1 it will be observed that other angled faces merge with the fulcrum receiving cut outs 4 and extend forwardly

downwardly therefrom. In the preferred form of my invention, shown in Figures 1 through 5 of the drawings, I provide each of the last named angled faces with a bore 5 for accommodating the yielding fulcrum retaining head 19 which projects outwardly from its shouldered and hollow cylindrical portion 20 and which is adapted to be held outward by the coiled compression spring 10 21, and to be moved inwardly, in its retaining casing 22, under the action of and for permitting the passing of the fulcrum pin 5, and against the action of the said spring 21, see Figure 5.

15 The casings 22 loosely fit the bores in the angled faces above referred to, and are held in the operative position shown in Figure 5 by the retaining screws 23, as shown.

In Figure 1 the invention is shown as adjusted to its narrowest working range and as exerting clamping action upon a small piece of work having flat parallel faces, see dotted lines.

In Figure 6, the invention is shown as adjusted to its increased working range and as exerting clamping action upon a larger piece of work including a tapered and rounded clamping face.

In the said Figure 6, a modified form of 30 fulcrum pin retaining means is employed, and the same is in the nature of a spring clip 24 arranged as shown with relation to the fulcrum pin 5, and the said spring clips are secured as at 25 to the angled faces 33 which merge with the fulcrum receiving portions 4.

It will be observed from Figures 2, 3, and 4 that no part of the mechanism of my improved clamp projects beyond the outside planes of the parallel plates 6, from which it will be readily understood that the clamp may, if desired, be clamped in turn, together with its clamped work, in a larger holding means, such as a vise, with full advantage of the convenience of the feature above referred to.

It will be also readily understood how quickly and effectively the fulcrum pin 5 of the movable jaw carrying member may be snapped out of one fulcrum receiving portion 4 into another such portion for making the desired adjustment. It will be seen also that the clamping screw 10 may be utilized as a lever in effecting the above mentioned fulcrum changing action. By using the bearing socket 13 as a fulcrum the head 11 may be swung forwardly or backwardly, as the case may be, to cause the snapping of the fulcrum pin 5 into or out of the receiving portions 4. This action is not necessary and the user may readily accomplish the desired result without the aid of the action above described.

By reason of the positions of the fulcrum receiving portions 4, the co-relation thereof

with the angled faces, and the retaining means mounted on said faces, the fulcrum pin 5 is removably held within its respective receiving portion 4 and in a manner for most effectively supporting the thrust set 70 up by the clamping action.

From the foregoing description, taken in connection with the accompanying drawing, the novel details of construction, the operation and advantages of my invention will be 75 readily apparent to those skilled in the art to which the same relates.

What I claim is:

1. A clamp of the class described, comprising a relatively fixed jaw, a movable jaw, 80 means for fulcruming said jaws together to cooperate with each other, and means whereby said fulcrum may be adjusted and retained at its adjustment by snap action.

2. A clamp of the class described comprising a relatively fixed jaw, a movable jaw, a screw and a pivot head for moving said jaws toward each other to clamp the work, means for fulcruming said jaws together in cooperative relation, and means 90 whereby said fulcrum may be adjusted and retained at its adjustment by snap action.

3. A clamp of the class described comprising a relatively fixed jaw, a movable jaw carrying member having a pivoted clamping 95 jaw with clamping faces, a screw and a pivot head for moving said jaws toward each other to clamp the work, means for fulcruming said jaws together in cooperative relation, and means whereby said fulcrum may 100 be adjusted and retained at its adjustment by snap action.

4. A clamp of the class described comprising a relatively fixed base member providing 105 a clamping jaw, an upward projection provided with a plurality of fulcrum portions, fulcrum retaining means cooperative with said fulcrum portions, a movable clamping jaw carrying member, a fulcrum carried by said movable member, a pivoted clamping 110 jaw having clamping faces carried by said movable member, and means for causing clamping action by said clamping jaws.

5. A clamp of the class described comprising a relatively fixed base member providing a clamping jaw, an upward projection provided with a plurality of fulcrum portions, and a bearing socket, fulcrum retaining means cooperative with said fulcrum portions, a movable clamping jaw carrying member, a fulcrum carried by said movable member, a pivoted clamping 115 jaw having clamping faces carried by said movable member, and means for causing clamping action by said clamping jaws, said 120 means comprising a clamping screw having a turning head, and a bearing socket engaging end, a pivoted head carried by the movable clamping jaw carrying member 125 and having a threaded bore through which 130

the screw passes to engage the bearing socket of the relatively fixed base member.

6. A clamp of the class described comprising a relatively fixed base member providing a clamping jaw, an upward projection provided with a plurality of fulcrum portions, fulcrum retaining means cooperative with said fulcrum portions, said means comprising fulcrum retaining heads, casings for retaining the heads, means for retaining the casings and means for forcing the said heads outwardly into the fulcrum portions, a movable clamping jaw carrying member, a fulcrum carried by said movable member, a pivoted clamping jaw having clamping faces carried by said movable member, and means for causing clamping action by said clamping jaws.

7. As a new article of manufacture, a clamp comprising a relatively fixed base member providing a clamping jaw, an upward projection provided with a plurality of fulcrum portions, and a bearing socket, fulcrum retaining means cooperative with said fulcrum portions, said means comprising fulcrum retaining heads, casings for retaining the heads, means for retaining the casings and means for forcing the heads outwardly into the fulcrum portions, a movable clamping jaw carrying member, a fulcrum carried by said movable member, a pivoted clamping jaw having faces carried by said movable member, and means for causing clamping action by said clamping jaws.

8. A clamp of the class described comprising two cooperating members which are separable from each other by snap action and which include a relatively fixed jaw, a movable jaw, a screw and a pivot head for moving said jaws toward each other to clamp the work, means for fulcrumming said jaws together in cooperative relation, and means whereby said fulcrum may be adjusted and retained at its adjustment by snap action.

9. As a new article of manufacture, a clamp comprising two cooperating members which are separable from each other by snap action and which include a relatively fixed base member providing a clamping jaw, an upward projection provided with a plurality of fulcrum portions, and a bearing socket, fulcrum retaining means cooperative with said fulcrum portions, a movable clamping jaw carrying member, a fulcrum

carried by said movable member, a pivoted clamping jaw having clamping faces carried by said movable member, means for causing clamping action by said clamping jaws, said means comprising a clamping screw having a turning head and a bearing socket engaging end, a pivoted head carried by the movable clamping jaw carrying member and having a threaded bore through which the screw passes to engage the bearing socket of the relatively fixed base member.

10. As a new article of manufacture, a clamp comprising two cooperating members which are separable from each other by snap action and which include a relatively fixed base member providing a clamping jaw, an upward projection provided with a plurality of fulcrum portions, fulcrum retaining means cooperative with said fulcrum portions, said means comprising fulcrum retaining heads, casings for retaining the heads, means for retaining the casings, means for forcing the said heads outwardly into the fulcrum portions, a movable clamping jaw carrying member, a fulcrum carried by said movable member, a pivoted clamping jaw having clamping faces carried by said movable member, and means for causing clamping action by said clamping jaws.

11. As a new article of manufacture, a clamp comprising two cooperating members which are separable from each other by snap action and which include a relatively fixed jaw, a movable jaw, means for fulcrumming said jaws together to cooperate with each other, and means whereby said fulcrum may be adjusted and retained at its adjustment by snap action.

12. A clamp of the class described comprising a relatively fixed jaw, a movable jaw carrying member composed of spaced parallel side plates, a pivoted clamping jaw having clamping faces carried by said movable jaw carrying member, a screw and a pivot head for moving said jaws toward each other to clamp the work, means for fulcrumming said jaws together in cooperative relation, means whereby said fulcrum may be adjusted and retained at its adjustment by snap, all of such elements being constructed and arranged so as to be inside the planes of the external faces of the spaced parallel side plates of the movable jaw.

WALTER S. TOWER.
